UNITED STATES PATENT OFFICE

114,535

DESIGN FOR A SAUCEPAN OR SIMILAR ARTICLE

Erik G. Grundstrom, Chicago, Ill., assignor to Advance Aluminum Castings Corp., Chicago,
Ill., a corporation of Illinois

Application May 6, 1938, Serial No. 77,037

Term of patent 14 years

To all whom it may concern:

Be it known that I, Erik G. Grundstrom, a citizen of the United States, residing at Chicago, in the county of Cook and State of Illinois, have invented a new, original, and ornamental Design for a Saucepan or Similar Article, of which the following is a specification, reference being had to the accompanying drawing, forming part thereof.

I claim:

The ornamental design for a saucepan or similar article, substantially as shown.

ERIK G. GRUNDSTROM.
